CLAIM

I claim the ornamental design for a module, as shown and described.

DESCRIPTION

FIG. 1 is a bottom perspective view of a module showing my new design;

FIG. 2 is a bottom elevation view of the module illustrated in FIG. 1;

FIG. 3 is a top elevation view of the module illustrated in FIG. 1;

FIG. 4 is a first side elevation view of the module illustrated in FIG. 1;

FIG. 5 is a second side elevation view of the module illustrated in FIG. 1;

FIG. 6 is a third side elevation view of the module illustrated in FIG. 1;

FIG. 7 is a fourth side elevation view of the module illustrated in FIG. 1;

FIG. 8 is a bottom perspective view of a module showing my new design;

FIG. 9 is a bottom elevation view of the module illustrated in FIG. 8;

FIG. 10 is a top elevation view of the module illustrated in FIG. 8;

FIG. 11 is a first side elevation view of the module illustrated in FIG. 8;

FIG. 12 is a second side elevation view of the module illustrated in FIG. 8;

FIG. 13 is a third side elevation view of the module illustrated in FIG. 8; and,

FIG. 14 is a fourth side elevation view of the module illustrated in FIG. 8.

In all of the FIGURES, the cross hatch represents a gold color, and the dashed lines represent a silver color.

1 Claim, 10 Drawing Sheets
